(57) **CLAIM**

The ornamental design for a bed frame connector set, as shown and described.

DESCRIPTION

FIG. 1 is a perspective view of a bed frame connector set showing my new design, shown in an environment of use; FIG. 2 is another perspective view thereof, shown in an environment of use;

FIG. 3 is a perspective view of one instance of the first component of the bed frame connector set, shown separately to reveal aspects of the design that are not visible in the other figures;

FIG. 4 is a front elevational view thereof;

FIG. 5 is a rear elevational view thereof;

FIG. 6 is a left view thereof;

FIG. 7 is a right view thereof;

FIG. 8 is a top view thereof;

FIG. 9 is a bottom view thereof;

FIG. 10 is a perspective view of one instance of the second component of the bed frame connector set, shown separately to reveal aspects of the design that are not visible in the other figures;

FIG. 11 is a front elevational view thereof;

FIG. 12 is a rear elevational view thereof;

FIG. 13 is a left view thereof;

FIG. 14 is a right view thereof;

FIG. 15 is a top view thereof;

FIG. 16 is a bottom view thereof;

FIG. 17 is a perspective view of one instance of the third component of the bed frame connector set, shown separately to reveal aspects of the design that are not visible in the other figures;

FIG. 18 is a front elevational view thereof;

FIG. 19 is a rear elevational view thereof;

FIG. 20 is a left view thereof;

FIG. 21 is a right view thereof;

FIG. 22 is a top view thereof; and,

FIG. 23 is a bottom view thereof.

The broken lines illustrate the environment and form no part of the claimed design.
